UNITED STATES PATENT OFFICE.

ROBERT S. LAWRENCE, OF WASHINGTON, DISTRICT OF COLUMBIA.

WAVE-POWER ACCUMULATOR.

SPECIFICATION forming part of Letters Patent No. 650,469, dated May 29, 1900.

Application filed July 28, 1899. Serial No. 725,398. (No model.)

To all whom it may concern:

Be it known that I, ROBERT S. LAWRENCE, a citizen of the United States, residing at Washington, in the District of Columbia, have invented certain new and useful Improvements in Wave-Power Accumulators or Motors, of which the following is a specification, reference being had therein to the accompanying drawings.

10 My invention relates to wave-power accumulators or motors, and the broad idea involved in the invention is to utilize the motion of the waves of the ocean to operate a pump of novel construction.

15 It has been proposed heretofore to employ apparatus upon the surface of the water to rise and fall with the waves, the motion thus produced being utilized for the operation of pumps or motors. Such apparatus, however, 20 is objectionable mainly for the reason that a storm or an unusually high tide quickly renders it inoperative or destroys it entirely.

An important characteristic of my invention is that it is designed to be entirely submerged to a depth sufficient to prevent damage from storms and high tides and to be operated directly by the horizontal force of the waves.

25 I employ a force-pump of the construction hereinafter fully described, in connection with a water-tank located on land and elevated a considerable distance above the beach, connected with the pump by pipes.

In the accompanying drawings, which form 30 a part of this specification, Figure 1 is a side elevation of an apparatus embodying the invention. Fig. 2 is a longitudinal section of the pump. Fig. 3 is an end elevation of the pump, and Fig. 4 is a transverse section 35 showing the inner side of the inner end of the outer head of the outer pump-cylinder.

40 Before describing the construction of the pump it may be premised that it is designed to employ a number of the pumps in groups 45 or batteries emptying into one or more tanks; but inasmuch as they will all be of the same construction a description of one will suffice.

The pump consists of two centric cylinders, 50 designated in the drawings by the reference-numerals 1 and 2, respectively, and preferably made of copper or other metal which will withstand the action of sea-water, or the

cylinders may be of wood with metallic linings or casings 3, as shown in the drawings. The outer cylinder 1 constitutes the water-containing chamber of the pump, while the inner cylinder 2 operates as a piston to force the water out of the cylinder 1. The cylinder 1 is open at one end, while its opposite end is closed by a head 4, formed with a plurality of water-inlets 5. These openings 5 are provided on the inner side of the head with flap-valves 6, hinged at their upper ends and capable of opening inwardly only. The head 4 is also formed with a discharge-opening 7, to which is attached one end of a water-pipe 8, leading to an elevated tank 9, into which the upper downwardly-turned end 10 of the pipe 8 empties. A second pipe 11 leads from the tank 9 to a small opening 12 in the head 4, said pipe being of much less diameter than the pipe 8 and designed for a purpose hereinafter explained. The inner cylinder 2 is closed at both ends by heads 13 and 14 and is guided in its movement by a plurality of telescoping tubes 15 and 16. The tubes 15 are secured at one end in suitable openings formed in the head 4, while the coöperating tubes 16 are secured to the outer head 14 of the cylinder 2. As clearly 50 illustrated in Fig. 2, the tubes 16 fit loosely within the outer tubes 15 to have a sliding telescopic motion. The two cylinders are also connected by a series of equidistant guide-rods 17, which are secured to the head 4, outside of the cylinder 1, and pass loosely through opening 18, formed in the head 14. The outer ends of these rods are connected by a ring 19, as shown in Fig. 1. The outer cylinder 1 is supported upon transverse bars 55 or supports 20, constituting part of a protecting pile structure or breakwater 21, which incloses the pump, and said cylinder 1 is thus held stationary.

The operation of the apparatus may be described as follows: As a wave recedes the flap-valves 6 are opened, allowing the cylinder 1 to fill with water. The pressure of the water against the head 13 of the inner cylinder 2 forces the latter outwardly. The next 60 incoming wave then strikes the outer side of the head 14, forcing the cylinder 2 inward, and thus ejecting the water in the cylinder 1 out through the pipe 8 and elevating it to the

- tank 9. It will be obvious that the pressure of water against the valves 6 holds them closed, so that the only escape for the water is through the outlet-pipe 8 and small pipe 11.
- 5 To guard against the return of water to the cylinder 1 from the pipe 8, I provide within the latter one or more flap-valves 22, which will readily open as the water is forced up through the pipe, but will automatically close against
- 10 back pressure of the water. While ordinarily the inflow of water through the openings 5, caused by a receding wave, will suffice to move the cylinder 2 outward, I have provided the pipe 11 as a supplemental means for this
- 15 purpose. A small stream of water falls through this pipe 11 to give the initial impetus or force against the head 13.
- It will of course be understood that the water collected in the tank 10 by the pumping
- 20 apparatus will be utilized by turbine water-wheels or other mechanism to run dynamos or other machinery, the specific means for this purpose not constituting a part of the present invention.
- 25 I claim—
1. A wave-motor comprising a cylinder, piston and automatic valves controlling the ingress of water to move the piston and a delivery-pipe leading from the cylinder.
  - 30 2. A wave-motor comprising a piston, a cylinder having an opening at one end for the admission of water to drive the piston, and means for imparting an initial impetus to the piston.
  - 35 3. A wave-motor comprising a piston, a cylinder having an opening at one end for the admission of water to reciprocate the piston, and means for injecting water into the cylinder as supplemental piston-actuating means.
  - 40 4. A wave-motor comprising a cylinder, a piston, means for leading water from the piston, and means for returning a portion of the water to the cylinder to impart an initial impetus to the piston.
  - 45 5. A wave-motor comprising a cylinder having valve-controlled openings, a delivery-pipe, a reservoir, a return-pipe leading from the reservoir to the cylinder and a piston within the cylinder.
  - 50 6. A wave-motor comprising a piston, a cyl-

inder having an opening at one end for the ingress of water, an elevated reservoir and a pipe leading from the reservoir to the cylinder for the injection of water under pressure to impart an initial impetus to the piston.

55

7. A wave-power accumulator comprising two concentric cylinders arranged one within the other, the outer cylinder being open at one end, and provided at its opposite end with water-inlets; automatic valves for closing

60 said inlets; a delivery-pipe leading from the outer cylinder to a water-tank and means for guiding the inner cylinder in its movement.

8. The combination with a fixed cylinder

65 open at one end and provided at its closed end with water-inlets; of a delivery-pipe and a receiving-tank; automatic valves for closing the water-inlets; a movable cylinder arranged within the fixed cylinder and closed

70 at both ends; and means for guiding the movable cylinder in its movement.

9. The combination with a fixed cylinder open at its outer end and provided at its closed end with water-inlets; of a delivery-pipe and

75 a receiving-tank; automatic valves for closing the water-inlets; a movable cylinder arranged within the fixed cylinder, and a series of telescoping tubes for guiding the movable cylinder.

10. The combination with a fixed cylinder open at one end, and formed at its closed end with valved water-inlets, a discharge-opening, and a supplemental water-inlet, of a movable cylinder closed at both ends and arranged within the fixed cylinder; longitudinal guides for said movable cylinder; a receiving-tank elevated above the cylinders; a water-discharge pipe, connecting the discharge-opening of the fixed cylinder with the

85 tank; and a return-pipe connecting the tank with the supplemental inlet of the fixed cylinder.

In testimony whereof I affix my signature in presence of two witnesses.

ROBERT S. LAWRENCE.
